UNITED STATES PATENT OFFICE.

ENGLEBERT A. BARTEL, OF BROOKLYN, NEW YORK, ASSIGNOR TO P-W DEVICE CORPORATION, OF BROOKLYN, NEW YORK, A CORPORATION OF NEW YORK.

PLATE AND DIE HOLDER FOR EMBOSSED MACHINES.

Application filed December 3, 1927. Serial No. 237,404.

This invention relates to embossing machines using engraved dies and plates in general and more especially to the holders for dies and plates.

5 Among the objects of the present invention it is aimed to provide a holder for engraved copper or steel plates, dies and the like for use in printing machines such as embossing machines, by means of which holder 10 the plate or die can with facility be secured in place and be readily adjusted both laterally and longitudinally relative to the counter and ink roll lifting cams.

The present invention further aims to provide a holder that can be readily adapted to a standard embossing machine of the type today used for printing from engraved steel and copper plates and the like.

These and other features, capabilities and 20 advantages of the invention will appear from the subjoined detail description of one specific embodiment thereof illustrated in the accompanying drawings, in which

Figure 1 is a plan of the improved plate 25 holder;

Fig. 2 is a section on the line 2—2 of Fig. 1; and

Fig. 3 is a schematic view showing the position of the engraved plate relative to 30 the plate holder, counter and inking rolls, with a part of the counter and counter holder in section spaced from and disposed above the plate holder and path of movement of the inking roller.

35 In the embodiment illustrated, the supporting plate 1 indicates the standard supporting plate of an embossing machine which is provided with a channel 2 in which is located the threaded portion 3 of the screw 4. The 40 screw 4 is generally provided with a key receiving nut 5 at its end adjacent to which there is formed a shoulder 6 which is spaced from the collar 7 a distance equal to the anchoring bar 8 through which the neck 9 of 45 the screw 4 extends, and which anchoring bar 8 is secured to the end of the supporting plate 1 for the work.

The threaded portion 3 is preferably a right hand thread, as shown, cooperating with the 50 internally threaded portion 10 of the lug 11 traveling in the channel 2 and extending from the bottom of the main plate portion 12 of the plate holder. On the main plate portion 12 the engraved plate or die is positioned, and 55 by means of the cooperation of the screw 4

with the lug 11, the position of the engraved portion on the engraved plate P, illustrated by the dash and dot line in Figs. 1 and 2, is adjusted longitudinally relative to the counter 13 on the counter holder 14, see Fig. 3, 60 also the ink roll lifting cams and also the space S, S', between the pairs of ink roll lifting cams 15, 16, and 17, 18, respectively.

In the standard form of machine, the ink roll lifting cams are longitudinally adjustable, having the slots 19 and being secured to the lateral edges of the supporting plate 1 by means of the screws 20. The ink roll lifting cams heretofore have been supported laterally adjustable in order that the spaces 70 S, S', may register with the engraved portion on the engraved plate and also register with the counter on the counter holder. In the present instance, the adjustable feature of the ink roll lifting cams in most cases may 75 be dispensed with since its adjustable feature is now taken care of by the cooperation of the screw 4 with the lug 11. The advantage of this one-point adjustment, to wit the adjustment of a single screw 4 as compared to 80 the former adjustment of the four screws 20, is of course obvious. The adjustable element of the ink roll lifting cams of course also serves to provide a greater or less inking space S, S', to accord with the engraved 85 area on the engraved plate P. For this purpose the adjustable feature of the ink roll lifting cams is of course retained.

Since the main plate portion 12, in the present instance, is considerably larger than 90 the supporting plate generally provided with the embossing machine, it is preferable, as illustrated, to provide lifting cams which extend well beyond the front edge 21 and the rear edge 22 of the plate portion 12 so that 95 the inking roll can in no way engage any portion of the plate portion 12 except the engraved portion of the plate P intended to be inked. Successive positions of the inking roll 23 are indicated in Fig. 3 by the dash 100 and dot positions 23^a, 23^b and 23^c.

For anchoring the engraved plate P in position on the main plate portion 12, the construction now to be described is provided:

The main plate portion 12 is provided 105 with a cylindrical channel 24 which extends the full length of the plate portion 12 from the edge 21 to the edge 22. This channel 24 is provided with a diminished slot 25 emerging longitudinally of said plate por- 110

tion 12. In the channel 24 there extends the screw threaded portion 26 of the screw 27, which screw threaded portion 26 is left handed and cooperates with the internally threaded portion of the cylindrical member 28, preferably composed of suitably heat-treated tool steel, which has radially extending therefrom a spur-like element 29 which travels in the slot 25, the rear face of which is preferably slightly undercut to form an acute angle with the periphery of the cylindrical portion 28 so that its upper rear edge may constitute a gripping plate engaging edge when engaging the front edge of the engraved plate P, see Figs. 1 and 2.

For operating the screw 27 knurled handle portion 30 is provided. To anchor the screw 27 in the plate portion 12 it is provided with a collar 31 which is located in the slot formed by the recesses 32 and 33 of the complementary sections 34 and 35 respectively. The sections 34 and 35 are preferably screwed to the front edge 21 of the plate portion 12 by means of the screws 36, 36, and 37, 37, respectively.

The rear end of the channel 24 is preferably closed by the screw member 38 to bar the entrance of ink and the like through such rear end.

The present invention also aims to provide a three-point contact for the engraved plate P in order to facilitate lateral adjustment of the same, and the ready and expeditious anchoring of the plate P in adjusted position. The three-point locking contact includes the spur 29 and the two abutment members 39 and 40. The abutment members 39 and 40 are preferably composed of suitably heat-treated tool steel. In the present instance, the plate portion 12 is provided with the recesses 41 and 42 to receive the abutment members 39 and 40 respectively. The abutment members 39 and 40 are provided with upwardly extending ledges 43 which have forward faces 44 slightly undercut to form a gripping surface at the upper edge of the abutment members, and rear rounded portions 45 which extend from the faces 44 to the rear lower faces of the abutment members 39, 40. The abutment members 39, 40, are preferably secured to the plate portion 12 by means of screws such as screw 46 illustrated in Fig. 2.

The narrow slot 25 is so narrow that the engraved plate P, which is generally composed of very thin stock about nineteen gauge, will rigidly span such slot 25 and not be distorted when subjected to the printing impress. In other words, it has been found that when this slot is not extremely narrow, as illustrated, the printing plate P will during the printing operation be pressed into such slot and the plate thereby distorted.

When providing two abutment members 39 and 40 of comparatively short contact faces, the plate locking function is in no way im-

paired and at the same time a comparatively low priced construction provided which can be readily repaired at low cost.

By means of the spur 29 and the abutment members 39 and 40, it is obvious that the lateral adjustment of the plate P relative to the main plate portion 12 can be readily effected by merely manipulating the screw member 27 to free the plate P and thereupon move the plate P in contact with the edges 39 and 40 to the desired position, whereupon the screw will again be manipulated to cause the spur 29 to anchor the plate P between it and the abutment members 39 and 40.

It is of course understood that the size of the engraved plate P illustrated, is merely indicative of one of the sizes of engraved plates that can be used with the present invention, and that one of the features of the present invention resides in the fact that it lends itself readily to accommodate itself to various sizes of engraved plates.

It is obvious that various changes and modifications may be made to the details of construction without departing from the general spirit of the invention as set forth in the appended claims.

I claim:

1. The combination with the work supporting plate of an embossing machine, of a main screw operatively associated with said plate, a main plate portion operatively connected to said main screw to be adjusted longitudinally of said supporting plate, fixed jaw means on said plate portion, a movable jaw means, and a second screw carried by said plate portion and operably associated with said movable jaw means to anchor the work to said plate portion between said fixed jaw means and said movable jaw means.

2. The combination with the work supporting plate of an embossing machine, of a main screw operatively associated with said plate, a main plate portion operatively connected to said main screw to be adjusted longitudinally of said supporting plate, fixed jaw means on said plate portion, movable jaw means adjustable longitudinally of said plate portion, and a second screw carried by said plate portion and operably associated with said movable jaw means to anchor the work to said plate portion between said fixed jaw means and said movable jaw means and to facilitate adjustment of the work laterally of said plate portion.

3. The combination with the work supporting plate of an embossing machine, of a main screw operatively associated with said plate, a main plate portion operatively connected to said main screw to be adjusted longitudinally of said supporting plate, fixed jaw means at one end of said plate portion, there being a channel extending longitudinally of said plate portion and having a narrow slot extending longitudinally of said plate por-

tion and emerging in the upper face of said plate portion, a second screw located in the channel of said plate portion, and a spur operatively associated with said second screw 5 and extending through said slot to form a movable jaw means to cooperate with the fixed jaw means to anchor the work to said plate portion and to permit lateral adjustment of the work relative to said plate por- 10 tion.

4. The combination with the work supporting plate of an embossing machine, of a main screw operatively associated with said plate, a main plate portion operatively connected to 15 said main screw to be adjusted longitudinally of said supporting plate, two gripping abutments spaced from one another and secured to said plate portion, there being a channel extending longitudinally of said plate por- 20 tion, said channel having a narrow slot emerging in the face of said plate portion and extending in a line that extends between said gripping abutments, a second screw located in said channel, and a movable gripping member operatively associated with said 25 second screw and extending through said slot to cooperate with the gripping abutments to anchor the work to said plate portion and to permit lateral adjustment of the work rela- 30 tive to said plate portion.

5. The combination with the work supporting plate of an embossing machine, of a main plate portion operatively connected to said supporting plate to be adjusted longitudi-

nally of said supporting plate, two gripping 35 abutments spaced from one another and secured to said plate portion, there being a channel extending longitudinally of said plate portion, said channel having a narrow slot emerging in the face of said plate por- 40 tion and extending in a line that extends between said gripping abutments, a screw located in said channel, and a movable gripping member operatively associated with said screw and extending through said slot to co- 45 operate with the gripping abutments to anchor the work to said plate portion and to permit lateral adjustment of the work relative to said plate portion.

6. The combination with an embossing ma- 50 chine having inking rolls, a holder for a counter, and a work supporting plate, of ink roll lifting cams adjustably connected to said sup- 55 porting plate and cooperating with said inking rolls to permit inking only a predetermined portion of the work, a screw operatively associated with said supporting plate, a main plate portion, and anchoring means associated with said plate portion for anchor- 60 ing the work to said plate portion, said plate portion being operatively connected to said screw to be adjusted longitudinally of said supporting plate to facilitate registering the work carried by said plate portion with the counter and inking space between said lifting 65 cams.
